UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

MULTIPLE-WIDTH PRINTING PRESS

Application filed August 4, 1923, Serial No. 655,772. Renewed March 27, 1929.

This invention relates to a printing machine having a width much greater than is usual, to permit the simultaneous printing of a plurality of webs.

5 The chief object of the invention is to provide for making such a machine practical by providing means whereby the printing and plate cylinders and the ink roll can be steadied at points intermediate their bearings to prevent their springing and reduce vibration and consequent imperfections in the product.

10 The invention also involves details of the means for accomplishing this result, the combination of a plurality of supports for the cylinders, and the provision of special form rollers to cooperate with them.

Reference is to be had to the accompanying drawings, in which

15 Fig. 1 is a longitudinal sectional view of a part of a printing press showing the features to which this invention is adapted to be applied and illustrating in detail certain of the supports;

20 Fig. 2 is a similar view of the other end of this part of the machine showing a modified form of plate cylinder steadyng means;

25 Fig. 3 is a plan looking in the direction of the arrow 3 in Fig. 1;

30 Fig. 4 is a sectional view of the ink fountain on the line 4—4 of Fig. 1;

35 Fig. 5 is a plan of one of the printing couples showing the form roll therefor slightly displaced to enable it to be shown in this view;

40 Figs. 6 and 7 are enlarged sectional fragmentary views of a portion of the plate cylinder showing two forms of margin rings for cooperation with the steadyng device, and

45 Figs. 8, 9 and 10 are similar enlarged sectional fragmentary views of the impression cylinder showing three forms of margin rings therefor, all constructed in accordance with this invention. Figs. 5, 6 and 9 show the one form of rings, and Figs. 1, 3, 7 and 10 another form.

I have shown the invention as applied to a perfecting web press comprising two plate cylinders 10 and two impression cylinders 11, arranged in a well known way. They are used, of course, with an ink fountain 12, ink

roll 13, ink cylinder 14, distributing rolls 15, and a pair of form rollers 16 at each end of the press. The ink fountain as usual is provided with the ductor roller 17 and with a back 57 and scraping blade 58 adjustable by 55 screws 59. Of course, these rolls and cylinders are supported in end bearings that necessarily are far apart.

As stated, this invention is intended to be used on a wide press and I have shown it as 60 applied to a press having three times the width of the usual press for printing on both sides of three webs simultaneously. This involves the lengthening of the plate and impression cylinders, as well as the ink cylinder and ink roll, to such an extent that if 65 made as the corresponding members are usually made, they would be apt to spring at points between their bearings, and thus interfere with the clearness of the product. This invention relates mainly to the provision of means for preventing this springing and in 70 fact reducing all vibration.

In the first place the ink roll is supported at one or more points between its bearings, 75 which are far apart, by an idle supporting roller 60. This roller in each case is provided with integral studs 61 which project around them or around master studs of the same size and shape. This roller 60 is located and of such size that it bears directly on the bottom of the ink roll at a convenient point and holds the same up so that it cannot spring in that direction or sag between its bearings. 80 This roller 60 is supported in an offset 63 at the bottom of the ink fountain and operates in the ink at all times. The drain plug 64 can be located conveniently in this offset as it is the lowest point in the ink fountain. 85

Each of the plate cylinders 10 is shown as divided into three parts, each part being adapted to carry two plates 65 if desired, these plates being placed on the cylinders in the usual way and each pair of plates occupying the same space as is usual in a single page width press of the ordinary type. Between each pair of plates, or between each two adjacent sections of the plate cylinder, I provide 90 spaces for margin rings 66. These margin 95 rings 66 are of the usual type and are used to 100

5 rings are located in circumferential recesses in the plate cylinders and extending around them. They are provided with overhanging edges 67 angularly shaped to overlap the corresponding edges of the plates 65 and hold them in position on the cylinder.

10 The main body of each ring is located below the printing surface of the cylinder or rather of the plates thereon, but each one has a cylindrical contacting surface 68 extending all the way around it which can be located in various ways. In Fig. 6 I have shown this contacting surface 68 as located above the printing surfaces, that is, it projects beyond them a uniform distance all the way around. 15 In Fig. 7, I have shown the corresponding contacting surface 69 as located below the printing surface. Both of these forms come within the scope of this invention.

20 Each of the impression cylinders of course, is provided with the usual blanket 70 which is arranged to extend a sufficient distance beyond the metallic surface of the cylinder to bring it to a certain height or diameter. 25 These blankets are arranged in series, one for each section of the cylinder. Between the ends of each two adjacent blankets is a bearing ring 71. For the purpose of cooperating with a plate cylinder like that shown in Fig. 30 6, the bearing ring 71 is sunk not only into the surface of the impression cylinder but its bearing surface is sunk below the bearing surface of the blankets a sufficient distance to permit the projecting contacting surface 35 68 in Fig. 6 to contact therewith at all times. This prevents the springing of one cylinder independently of the other and yet neither cylinder is crowded over out of its normal position.

40 For the purpose of cooperating with such a contacting surface as 69, in Fig. 7, I have shown the bearing ring in Fig. 10 with its bearing surface projecting above the bearing surface of the blankets. It is not necessary to have either of these constructions, as in Fig. 45 8 I have shown a printing cylinder 10 and impression cylinder 11 with a margin ring 72 on the former and a bearing ring 73 on the latter exactly of the respective sizes of the 50 plates on one cylinder and blankets on the other. In all these cases the respective margin rings and bearing rings are in contact with each other at all times between the ends of the plates and of the blankets. They are 55 located in this way to prevent the springing of these cylinders with respect to each other as stated.

60 It is to be observed that the four cylinders are located in contact in series along the press and that the two plate cylinders which are on the outside are also provided with margin supports 74 at opposite points. These margin supports are merely projections on the frame 65 of the printing press provided with means

for bearing on the margin rings 66 of the respective plate cylinders.

70 In the form shown in Fig. 1 each one comprises brackets 75 bolted to the margin support through slots 76 in the brackets and adjusted toward or from the plate cylinder by screws 77, the operation of which will be obvious. On each bracket is mounted a roll 78 adapted to bear directly on one of the bearing surfaces 69 of the margin ring 66. 75 There are as many of these rolls as there are margin rings in the length of the plate and they constitute positive means for preventing the plate cylinder springing back toward the margin support.

80 At the other end a similar arrangement is provided. In Fig. 2 I have taken occasion to show a modified form of margin support 80 constituting a part of the frame, and having a roll 81 and adjusting screws 82 for the same purpose as the corresponding parts 78 and 77 just described. The roll 81 is mounted on a link 83 pivoted on a stud 84 on the margin support 80. This link has a projection 88 against which the screw 82 engages to hold the roll up to its margin ring. Ordinarily 90 the same form of margin support will be used on both ends of the same press, but either form can be employed.

95 It will be seen, therefore, that the margin supports 74 or 80 with their cooperating parts act oppositely to prevent the whole series of cylinders yielding between their bearings in opposite directions so that all of them are held against moving in any direction out of their circular orbit.

100 The pressure is transmitted in opposite directions throughout the series of plate and impression cylinders by the margin rings which are mounted firmly on their respective cylinders. In this way the vibration and displacement that otherwise would take place is avoided and it is made practical to provide a press having a width equal to several newspaper page widths. At the same time a construction is provided, simple and inexpensive, and the total cost of these parts of such a press is very little more than the total cost of the same parts of a single press of the same type.

105 110 It is to be noticed that the bearing rings 71 on the two adjacent impression cylinders bear on each other in the preferred form shown in Figs. 1, 2, 7 and 10, to transmit the pressure across the two couples. The rings 71 in this case project beyond the impression surface and the form rollers 16 are provided with circumferential grooves 79 to receive them.

115 120 With the ring on the impression cylinder larger than the pitch diameter of the impression cylinder, the ring on the plate cylinder is smaller than plate circumference. Therefore, there is no inking on the ring on the plate cylinder. The slippage is immaterial.

125 130 Although I have illustrated and described two single forms of this invention I am aware

of the fact that other modifications can be made therein by any one skilled in the art without departing from the scope of the invention as expressed in the claims.

5 Therefore, I do not wish to be limited to all the details of construction herein shown and described, or to the particular type of press illustrated, but what I do claim is:—

1. In a web perfecting press, the combination of two printing couples, each comprising a plate cylinder and an impression cylinder of a length sufficient to permit of the printing of a plurality of page widths, said cylinders being arranged along the machine in 10 contact with each other, with means on said cylinders intermediate of the printed products for transmitting any thrust from one cylinder to the next in either direction, and means located in fixed position on the frame 15 of the machine at the opposite ends of said series of cylinders for bearing on said cylinders and preventing vibration thereof, whereby the vibration of the intermediate cylinders is also reduced.

25 2. In a printing press, the combination with a plate cylinder bearing a plurality of rows of printing plates and an impression cylinder, of bearing rings on said cylinders between the rows of printing plates and contacting directly with each other for transmitting thrust from either cylinder to the other and reducing vibration, and rollers mounted in stationary bearings at opposite 30 ends of the frame each in firm contact with one of said rings for receiving the thrust therefrom.

3. In a printing press, the combination with a plate cylinder bearing a plurality of rows of printing plates and an impression 40 cylinder, of bearing rings on said cylinders between their printing surfaces contacting directly with each other for transmitting thrust from either cylinder to the other and preventing vibration, rollers mounted in stationary bearings at opposite ends of the frame 45 of the machine each in firm contact with one of said rings for receiving the thrust therefrom, and means for adjusting said rollers toward and from the cylinder to insure firm 50 contact with the ring.

4. A web perfecting press having two printing couples, the impression cylinders having circumferential surfaces higher than the rest of the impression surfaces and arranged with the highest surfaces of the two impression cylinders in contact to transmit the thrust and reduce vibration.

In testimony whereof I have hereunto affixed my signature.

60 HENRY A. WISE WOOD.
